AUTOMOBILE WHEEL

Paul J. Mochel, Studio City, Calif., assignor to Electronic Specialty Company, a corporation of California

Filed July 14, 1965, Ser. No. 86,156

Term of patent 14 years

(Cl. D14—30)

FIG. 1.

FIG. 2.

FIG. 1 is a perspective front view of an automobile wheel showing my new design;

FIG. 2 is a back view thereof; and,

FIG. 3 is a side elevational view taken from the right-side of FIG. 2.

What I claim is:

The ornamental design for an automobile wheel, as shown.
